UNITED STATES PATENT OFFICE.

JOHN MOLONEY, OF OIL CITY, PENNSYLVANIA, ASSIGNOR OF ONE-FOURTH
HIS RIGHT TO PATRICK SAXTON AND JOHN C. WELCH, OF SAME PLACE.

IMPROVEMENT IN TUBINGS FOR OIL-WELLS.

Specification forming part of Letters Patent No. 142,861, dated September 16, 1873; application filed
February 1, 1873.

To all whom it may concern:

Be it known that I, JOHN MOLONEY, of Oil City, in the county of Venango and State of Pennsylvania, have invented certain Improvements in Tubing for Oil-WellS, of which the following is a specification:

My invention consists in applying a yielding support or step to the lower end of the tubing of oil-wells, for the purposes of relieving the tubing from strain, preventing its vibration, and preventing the tubing from telescoping or wedging fast in case it separates, as hereinafter fully described.

The drawing represents a vertical central section through my support applied to the tubing of a well.

In the operation of oil-wells it is the general practice to suspend the tubing freely within the well by means of a collar or flange at the top, the lower end of the tubing being held above the bottom of the well, and the entire weight of the tubing sustained by the collar at the top. To this arrangement there are serious objections, among which are, that the immense weight and strain upon the collar and the upper portion of the tubing cause frequent breakage and separation of the tubing; that the pipe, being free at the lower end, keeps up a constant vibratory or tremulous motion, which tends to loosen the joints; and that when the pipe separates it falls upon the solid bottom of the well and wedges fast therein.

To overcome these difficulties is the object of my invention, and I accomplish the desired end by simply applying a spring-support to the lower end of the tubing to sustain a portion of the weight.

In the drawing, A represents the ordinary tubing of a well, provided at its upper end with a collar or flange, a, and suspended thereby freely within the well in the usual manner. B represents a short outside pipe, secured, as usual, in the top of the well around the tubing, for the purposes of forming a bearing for the collar a, and of retaining the gas which ascends around the tubing. C represents my spring step or support, consisting of a tube or barrel, b, containing a spiral spring, c, and a piston, d, which bears upon and is

supported by the spring. The upper end of the barrel b is provided with a stuffing-box, e, around the piston, and is made tight at all other points, so as to exclude oil, water, &c., from the interior. The upper end of the piston d is provided with a screw neck or socket, by which to connect it to the tubing, and the lower end of the barrel b is also provided with a screw-neck, g, by which to attach supporting rods or pipes when necessary, as hereinafter described.

In using my support, its piston d is connected to the lower end of the well-tubing, or to the pump-barrel D, when the latter is attached to the foot of the tubing, as in the drawing, and then the tubing is lowered in the well until the support bears upon the bottom, and the piston and spring receive any desired proportion of the weight of the tubing. In cases where the tubing terminates at a considerable distance above the bottom of the well, my support may be upheld by attaching to its lower end extra tubing of sufficient length to bear upon the well-bottom; or the extra tubing may be connected to the lower end of the pump, and my support applied at the lower end of the extra tubing at the bottom of the well. As my support closes the end of the tubing or pump, it is necessary to employ a pump which has its body provided with inlet-openings in the sides, as shown.

The pump is applied in the ordinary manner to the tubing, at any desired point above the piston of my support.

The parts may be arranged so that the spring will sustain any desired portion of the weight; but care must be taken to leave sufficient weight on the collar to keep a gas-tight joint between it and its seat. By the use of my support the collar and the upper portion of the pipe are relieved from a great portion of the usual weight and strain, so that there is but little danger of the collar giving way, or of the pipe breaking or separating at the joints. The support, by holding the lower end of the tubing, prevents the same from swinging, and thereby prevents the tremulous motion ordinarily felt the entire length of the tubing, and which is one of the main causes of separation at the joints. When, however, the pipe

does separate, or from any other cause falls, its descent is checked by my spring-support without any shock or jar, so that it is prevented from telescoping, doubling up, or wedging fast in the well. Thus, it will be seen, I obviate the three great difficulties attending the operation of oil-wells on the present plan.

My device is cheap, simple, and durable; is applicable in existing wells without changing the well or tubing; and is in no way injurious or detrimental to the well, tubing, or pump.

It is obvious that the construction of the support may be varied, and that any other suitable form of spring may be used.

Having thus described my invention, what I claim is—

1. In combination with the tubing of an oil or other like well, a yielding support, C, constructed and arranged substantially as shown and described.

2. The support C for well-tubing, consisting of the body or barrel b, spring c, and piston d, when constructed substantially as shown and described.

JOHN MOLONEY.
